Primary Examiner — Jonathan J Han*Assistant Examiner* — Christen Pilar Brown(74) *Attorney, Agent, or Firm* — George D. Morgan(57) **CLAIM**

The ornamental design for a shoe, as shown and described.

DESCRIPTION

FIG. 1 is a front perspective view of a shoe, showing my new design;

FIG. 2 is a rear perspective view thereof;

FIG. 3 is a bottom perspective view thereof;

FIG. 4 is a right side view thereof;

FIG. 5 is a left side view thereof;

FIG. 6 is a rear view thereof;

FIG. 7 is a front view thereof;

FIG. 8 is a top view thereof; and,

FIG. 9 is a bottom view.

The broken lines shown on the shoe upper depict stitching, which does form a part of the claimed design. The broken lines showing the remainder of the shoe show portions that form no part of the claimed design.
